(57) **CLAIM**

I claim the ornamental design for a firearm case front cover, as shown and described.

DESCRIPTION

FIG. 1 is an isometric view of a firearm case front cover showing my new design.

FIG. 2 is a front elevation view thereof.

FIG. 3 is a rear elevation view thereof.

FIG. 4 is a right side elevation view thereof, with the opposite side being a mirror of that shown.

FIG. 5 is a top plan view thereof; and,

FIG. 6 is a bottom plan view thereof.

The broken lines shown in the drawing illustrate portions of the firearm case and form no part of the claimed design.
